Primary Examiner — Katherine Glennon(74) *Attorney, Agent, or Firm* — Rumit Ranjit Kanakia(57) **CLAIM**

The ornamental design for a moving gear wall clock, as shown and described.

DESCRIPTION

FIG. 1 is a perspective view of a moving gear wall clock showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the figures are for the purposes of illustrating portions of the moving gear wall clock, which form no part of the claimed design.

1 Claim, 6 Drawing Sheets(56)
